ABSTRACT: A housing, positioned at an edge of a moving strip, contains a source of light disposed on one side of said strip and first and second light-sensitive means, spaced apart from each other longitudinally of said strip, disposed on the other side of said strip. A light shield, positioned adjacent said edge of the strip, comprises a shielding element having an inner edge extending beyond the edge of the strip between said strip and said light-sensitive means. First and second apertures in said shielding element, spaced apart from each other both longitudinally and laterally of said strip, permit only light from said source passing through predetermined areas of said strip to impinge on said light-sensitive means. Circuits are provided for producing an output signal indicative of a crack only when a signal produced in response to light impinging on said first light-sensitive means precedes a signal produced in response to light impinging on said second light-sensitive means by the time required for the strip to travel from said first aperture to said second aperture.

CRACK DETECTOR FOR EDGE OF MOVING STRIP WHICH DISCRIMINATES BETWEEN CRACKS AND PINHOLES

BACKGROUND OF THE INVENTION

This invention relates to apparatus for detecting defects in strip, and more particularly to an edge crack detector which accurately distinguishes between edge cracks and pinholes in moving strip.

Steel strip which has been cold rolled is generally characterized by uneven edges and a width which is not constant along the entire length of the strip. In addition, small tears or cracks are occasionally present in the edges of the strip. Consequently, cold-rolled strip is generally passed through an edge-trimming machine to provide strip of a constant width with straight edges which are essentially free of cracks.

Edge cracks sometimes extend into that portion of the strip which remains after the edge-trimming operation. If the strip is to be fed subsequently into an electrolytic plating line, it is extremely important that these cracks be detected and proper remedial action taken prior to the plating operation, as any crack in the edge of the strip is likely to cause the strip to tear across its entire width if the strip is fed through the plating line at production speeds. Such remedial action may comprise cutting a crack out of an edge of the strip at a point immediately ahead of the plating line. The cut is generally crescent-shaped to reduce the stress at the edge of the strip and thereby decrease the probability of the strip tearing thereacross, and necessitates substantially decreasing the speed of the strip during the making of the cut. Slowing down the strip, of course, increases the costs of production.

In view of the likelihood of the strip tearing if a crack passes undetected into an electrolytic tinning line, it is essential for an edge crack detector to accurately detect all cracks. Furthermore, in order to avoid slowing down the line when there is no crack in the strip, it is essential for an edge crack detector to produce no signal in the absence of a crack. Prior edge crack detectors frequently produced signals as a result of pinholes in the strip.

It is an object of this invention to provide an edge crack detector which accurately distinguishes between edge cracks and pinholes in moving strip.

SUMMARY OF THE INVENTION

I have discovered that the foregoing object can be attained by providing a source of light on one side of a moving strip and first and second light-sensitive means on the other side of the strip in substantial alignment with said source of light, said light-sensitive means being spaced apart from each other longitudinally of said strip. Said first and second light-sensitive means are adapted to receive only light from said source which passes through first and second areas of said strip, respectively, said second area being spaced apart from said first area both longitudinally and laterally of said strip. Means are provided for producing a first signal indicating that light from said source has impinged on said first light-sensitive means and a second signal indicating that light from said source has impinged on said second light-sensitive means. Further means is provided for producing an output signal indicative of a crack only when said first signal precedes said second signal by the time required for the strip to travel from said first area to said second area.

BRIEF DESCRIPTION OF THE DRAWINGS

FIG. 1 is a side elevational view of the apparatus of the invention, partially cut away to show features thereof.

FIG. 2 is an end elevational view of the apparatus shown in FIG. 1.

FIG. 3 is a sectional view, taken along the lines 3-3 of FIG. 2, diagrammatically showing the salient features of the photosensitive control means for rough positioning of the subject apparatus relative to an edge of a moving strip.

FIG. 4 is a diagrammatic isometric view showing the general spatial relationship of the salient features of the invention.

FIG. 5 is a plan view diagrammatically showing the drive system for fine positioning the subject apparatus relative to a strip edge, while FIG. 6 is a side elevational view of the same.

FIG. 7 is a block diagram of the electrical circuits of the invention.

DESCRIPTION OF THE PREFERRED EMBODIMENT

As shown in FIGS. 1 and 2, a U-shaped housing 10 comprising an upper section 12 and a lower section 14 is disposed with portions of said upper and lower sections extending inwardly of the edge of a moving strip 16. The housing 10 is secured to a carriage 18 which is adapted to move transversely with respect to the path of the strip 16. The carriage 18 comprises an upper plate 20 which is spaced from a lower plate 22 by bolts 24 welded to said upper plate 20 which threadedly engage cooperating traveling nut pairs 26 whereby the spacing between said upper and said lower plates can be varied. Secured to the lower plate 22 by said bolts 24 and traveling nut pairs 26 are oppositely disposed angle irons 28 on which wheels 30 are rotatably mounted. Depending from the rear of the lower plate 22 is a vertical plate 32 to which a traveling nut 34 is secured.

A housing 36 is provided with means for driving and guiding the carriage 18 transversely relative to the direction of strip travel. Said housing 36 comprises a bottom channel 38 and side plates 40. Secured to each side plate 40 is a pair of longitudinally disposed angle irons 42 which receive the carriage wheels 30. A longitudinal guide strip 44 on the lower angle irons 42 prevents lateral movement of the carriage 18. Mounted on the bottom channel 38 is a motor 46 which is connected through a coupling 48 to a screw 50 supported at each end by bearings 52. The traveling nut 34 threadedly engages the screw 50 whereby rotation of said screw drives the carriage 18 transversely of the strip 16.

The motor 46 is controlled by photosensitive means contained in the boxlike housing 54 and 56 secured to the upper and lower sections 12 and 14, respectively, of the housing 10. As is shown more particularly in FIG. 3, the housing 54 contains three sources of light, viz., incandescent lamps 58, 60 and 62, each source being focused by a lens 64 on photosensitive means 66, 68 and 70, respectively. The photosensitive means 66, 68 and 70 are connected to circuits, not shown as they are well known in the art, which cause the motor 46 to drive the carriage 18 inwardly of the edge of the strip 16 until substantially no light from the lamp 58 impinges on photosensitive means 66. Should the strip 16 subsequently become narrower, thereby resulting in the illumination of means 66 by lamp 58, said circuits cause the motor 46 to drive the carriage 18 further inwardly until again there is no light from lamp 58 impinging on means 66. Should the strip subsequently become sufficiently wider whereby substantially no light from lamp 60 impinges on photosensitive means 68, said circuits cause the motor 46 to drive the carriage 18 outwardly until light from lamp 60 again impinges on means 68. Should no light from lamp 62 impinge on means 70, said circuits cause the carriage 18 to be completely retracted to its outermost position.

The above description relates to means for rough positioning a housing 10 relative to an edge of a moving strip 16. While said positioning has been described in connection with photosensitive controls, other types of controls for automatically positioning said housing are of course permissible.

As is shown diagrammatically in FIG. 4, the upper section 12 of the housing 10 contains a source of ultraviolet light 72 comprising first and second pairs of fluorescent lamps 74 and 76, respectively. The pair of lamps 74 is spaced from the pair of lamps 76 longitudinally of the strip 16. The upper section 12 is provided with windows 78 and 80 disposed directly below the pairs of lamps 74 and 76, respectively. For reasons which will become clear as the description proceeds, the window 78 is disposed closer to the front edge of the upper section 12 of the housing 10 than is the window 80.

Disposed in the top of the lower section 14 of the housing 10 is a pair of windows 82 and 84 in vertical registry with the

windows 78 and 80, respectively. The windows 82 and 84 comprise ultraviolet transmitting filters, thereby decreasing the probability that light from sources other than the ultraviolet light source 72 will enter the lower section 14. Housed in the lower section 14 in vertical registry with the windows 82 and 84 are first and second light-sensitive means, respectively, comprising photomultiplier tubes 86 and 88. Preferably, Fresnel lenses 90 and 91 are disposed between said windows and said photomultiplier tubes for focusing any light passing through the windows 82 and 84 on the active areas of the photomultiplier tubes 86 and 88.

A light shield 92, the drive system for which will be discussed later in connection with FIGS. 5 and 6, is interposed between the upper and lower sections of the housing 10, and is adapted to be driven along the top of the lower section 14 of said housing transversely of the direction of strip travel. The light shield 92 broadly comprises an upper shielding element 94, a lower shielding element 96, and a vertical plate 98 connecting said elements at the rear ends thereof. Mounted in the lower side of the upper shielding element 94 is a small source of light 100 which cooperates with a photosensitive cell 102 mounted in the upper side of the lower shielding element 96 to control the drive system for properly positioning the light shield 92 relative to the edge of the strip 16. The control circuit, not shown, may be similar to that disclosed in U.S. Pat. No. 3,263,086 to D. R. Brosious et al., issued Jul. 26, 1966, which utilizes the light impinging on a photosensitive cell mounted on a light shield to automatically maintain constant the position of said light shield relative to an edge of a moving strip.

The upper and lower shielding elements 94 and 96 are each provided with first and second apertures 104 and 106 therein, the apertures in the upper shielding element 94 being in vertical registry with those in the lower shielding element 96. During operation of the subject invention, the apertures 104 are adapted to be disposed between the windows 78 and 82 at all times, while the apertures 106 are adapted to be disposed between the windows 80 and 84 at all times.

It should be noted that the outer edges of apertures 106, i.e. the edges closest to the edge of the strip, are disposed closer to said edge than are the outer edges of the apertures 104. In the embodiment shown, said apertures are one-quarter inch square, the outer edges of apertures 106 are disposed three-eights of an inch from the edge of the strip, and the outer edges of apertures 104 are disposed three-quarters of an inch from said edge of the strip. Thus, there is a gap of one-eighth of an inch between the inner edges of apertures 106 and the outer edges of apertures 104 relative to the edge of the strip.

The outer edges of apertures 106 are disposed three-eights of an inch inwardly of the edge of the strip because the strip will subsequently be passed through an edge-trimming machine which removes three-eights of an inch from each edge of the strip. Thus, there is no need to inspect this portion of the strip. The apertures 106 are spaced from apertures 104, relative to the edge of the strip, so that only light from said source which passes through a first area of said strip will impinge on the photomultiplier tube 86, while only light from said source which passes through a second area of said strip will impinge on the photomultiplier tube 88. By reason of said first area being spaced apart from said second area both longitudinally and laterally of said strip, cracks deeper than three-quarters of an inch, e.g. crack 105, will be detected by the circuits of the invention while pinholes will not. How this is accomplished will become clearer as the description proceeds.

The drive system for the light shield 92 is shown diagrammatically in FIGS. 5 and 6. As shown, a rack 108 is secured by a bracket 110 to the vertical plate 98 connecting the upper and lower shielding elements 94 and 96, respectively. Rotatably mounted on the side of the rack 108 is a roller 112 which is adapted to rotate along a bearing plate 114 provided with mechanical stops 116. The side of the rack 108 rotatably engages a guide roller 118 mounted on the top of the rear of the lower section 14 of the housing 10. The rack 108 engages

a pinion 120 connected to the shaft of a motor 122 mounted in said lower section 14 and controlled by the aforementioned control circuits. The rack 108 is also provided with a stud 124 which is adapted to trip limit switches 126 and 128 which control the extent of motion of the light shield 92 within the housing 10. The mechanical stops 116 prevent damage to the strip 16 and the light shield 92 in the event of a malfunction of the limit switches 126 and 128.

The lower shielding element 96 is provided with rollers 130 which rotatably engage the top of the lower section 14 of the housing 10. In addition, said element 96 is provided with a cut out section 132 having longitudinal guide strips 134 which engage rollers 136 mounted on the top of the lower section 14 of the housing 10.

FIG. 7 shows a control circuit which produces an output signal in response to an edge crack deeper than three-quarters of an inch but which produces no output signal when a pinhole passes between either of the pairs of apertures 104 or 106.

Light passing through the apertures 104 impinges on the photomultiplier tube 86 and produces an output signal which is amplified by a preamplifier 138. The signal is then supplied to a power amplifier 140 having a low output impedance which matches the impedance of the digital logic circuits to which the signal is subsequently supplied. The output from the power amplifier 140 is supplied to a bistable switch 142 which produces an output gate signal.

Similarly, light passing through the apertures 106 impinges on the photomultiplier tube 88 and produces an output signal which is amplified by a preamplifier 144 and a power amplifier 146 having a low output impedance. Said signal is then supplied to a bistable switch 148.

Disposed immediately ahead of the light shield 92 is a strip-driven pulse tachometer 150. In the embodiment shown, the tachometer 150 produces 24 pulses per foot of strip travel. The output from the tachometer 150 is amplified by an amplifier 152, modified by a pulse shaper 154, and supplied to a gate 156.

In the absence of a signal from the bistable switch 142, the gate 156 is in its closed state; hence, none of the pulses from the pulse shaper 154 passes therethrough. However, when there is a gating signal from the bistable switch 142, as a result of light impinging on the photomultiplier tube 86, the pulses from the pulse shaper 154 pass through the gate 156 and initiate a preset counter 158 which is adapted to actuate a bistable switch 160 after a predetermined number of pulses. The number of pulses for which the counter 158 is set should correspond to the distance between the apertures 104 and 106. In the instant case, the center lines of said apertures are spaced 5 inches apart; hence, the counter 158 should be set for 10 pulses.

The output from the bistable switch 160 provides a gating signal which is supplied to a gate 162 connected to the output of the bistable switch 148. In response to the gating signal from the bistable switch 160, the gate 162 opens, thereby permitting a signal from the bistable switch 148 to pass therethrough and actuate output means 164 indicating that an edge crack deeper than three-quarters of an inch has passed through the light shield 92. The signal from the output means 164 may be utilized to mark a data record, sound a horn, illuminate a signal light, etc., whereby the approximate position of the edge crack may be recorded.

The signal from the bistable switch 160 is also utilized to open a gate 166 to which pulses from the pulse shaper 154 are supplied when the gate 156 is open. Said pulses pass through the gate 166 and initiate a preset counter 168 which is adapted to return the subject circuit to its initial condition, i.e., its condition prior to the passage of light through the apertures 104, a short time interval after the bistable switch 160 has been actuated. This time interval permits the strip to travel a few, e.g. 2, inches while the gate 162 is open, thereby allowing for some error in the calibration of the tachometer 150. To permit the strip to travel 2 inches while the gate 162 is open, the counter 168 is preset for four pulses, after which a signal therefrom

resets bistable switches 142, 148 and 160 and preset counter 158. Said signal also passes through a time delay 170 and subsequently resets preset counter 168. The time delay 170 allows sufficient time for the output signal from the preset counter 168 to reset the necessary circuits before the counter 168 itself is reset.

The above description of the subject circuit sets forth the operation thereof when an edge crack passes through the light shield 92. The following will set forth the operation thereof when a pinhole passes therethrough.

Inasmuch as the apertures 104 and 106 are spaced apart from each other laterally of the strip 16, a pinhole can never pass between both the apertures 104 and the apertures 106. If a pinhole passes between the apertures 104, the photomultiplier tube 86 will be actuated and the subject circuit will function, as above described, to open the gate 162. However, the bistable switch 148 will produce no output signal to pass through the gate 162 and actuate the output means 164, inasmuch as said pinhole did not subsequently pass between apertures 106 a predetermined time after passing between apertures 104. If a pinhole passes between the apertures 106, the photomultiplier tube 88 will be actuated and the subject circuit will function, as above described, to supply an output signal from the bistable switch 148 to the gate 162. However, said signal cannot pass through the gate 162 inasmuch as said gate is closed since said pinhole did not pass between the apertures 104 a predetermined time prior to passing between the apertures 106.

I claim:

1. Apparatus for detecting cracks in an edge of a moving strip, comprising:

- a. a source of light disposed on one side of said strip;
- b. first light-sensitive means, disposed on the other side of said strip, adapted to receive only light from said source which passes through a first area of said strip;
- c. second light-sensitive means, disposed on the other side of said strip, adapted to receive only light from said source which passes through a second area of said strip, said second area being spaced apart from said first area both longitudinally and laterally of said strip;
- d. means for producing a first signal indicating that light from said source has impinged on said first light-sensitive means;
- e. means for producing a second signal indicating that light from said source has impinged on said second light-sensitive means; and
- f. means for producing an output signal indicative of a crack only when said first signal precedes said second signal by the time required for the strip to travel from said first area to said second area.

2. Apparatus for detecting cracks in an edge of a moving strip, comprising:

- a. a source of light disposed on one side of said strip;
- b. first and second light-sensitive means disposed on the other side of said strip in substantial alignment with said source of light, said light-sensitive means being spaced apart longitudinally of said strip;
- c. means, interposed between said strip and said light-sensitive means, for permitting only light from said source which passes through a first and a second area of said strip to impinge on said first and second light-sensitive means, respectively, said first and second areas being spaced apart from each other both longitudinally and laterally of said strip;
- d. means for producing a first signal indicating that light from said source has impinged on said first light-sensitive means;
- e. means for producing a second signal indicating that light from said source has impinged on said second light-sensitive means; and
- f. means for producing an output signal indicative of a crack only when said first signal precedes said second signal by the time required for the strip to travel from said first area

to said second area.

3. Apparatus as recited in claim 2, in which means (c) comprises:

- a. light-shielding means, positioned adjacent said edge of said strip, comprising a shielding element having an inner edge extending beyond said edge of said strip between said strip and said light-sensitive means; and
- b. first and second apertures in said shielding element, said apertures being adapted to permit only light from said source which passes through said first and second areas, respectively, to impinge on said first and second light-sensitive means, respectively.

4. Apparatus as recited in claim 3, in which said light-shielding means further comprises a second shielding element, disposed between said source of light and said strip, having first and second apertures therein in registry with the apertures in the shielding element extending between said strip and said light-sensitive means.

5. Apparatus as recited in claim 1, in which means (f) comprises:

- a. gating means, connected to the output of means (e) adapted to be opened by a control signal supplied thereto;
- b. means, connected to said gating means, for producing a signal indicative of a crack only when a signal from means (e) passes through said gating means;
- c. means for producing pulses at a rate proportional to the speed of said strip; and
- d. means for counting said pulses only when the signal of means (d) is produced, and for supplying a control signal to said gating means whereby said gating means is opened for a short time interval after a predetermined number of said pulses have been counted.

6. Apparatus as recited in claim 4, in which means is provided for maintaining the position of said light-shielding means constant relative to said edge of said strip.

7. Apparatus for detecting cracks in an edge of a moving strip, comprising:

- a. a housing positioned adjacent said edge and adapted to move transversely with respect to the direction of strip movement, said housing comprising a first section which extends inwardly of said edge on one side of said strip and a second section in registry with said first section on the other side of said strip;
- b. a source of light disposed in said first section;
- c. first and second light-sensitive means disposed in said second section in substantial alignment with said source of light, said light-sensitive means being spaced apart from each other longitudinally of said strip;
- d. light-shielding means, positioned between said first and second sections of said housing and adapted to move in said housing transversely with respect to the direction of strip movement, comprising first and second shielding elements, in substantial registry, having an inner edge extending between said source of light and said strip and said light-sensitive means and said strip, respectively;
- e. first and second apertures in each of said shielding elements, said apertures being disposed in substantial alignment with said source of light and said first and said second light-sensitive means, respectively, and being spaced apart from each other both longitudinally and laterally of said strip;
- f. means connected to said light-shielding means for maintaining the position thereof constant relative to said edge of said strip;
- g. means for producing a first signal indicating that light has impinged on said first light-sensitive means;
- h. means for producing a second signal indicating that light has impinged on said second light-sensitive means; and
- i. means for producing an output signal indicative of a crack only when said first signal precedes said second signal by the time required for the strip to travel from said first aperture to said second aperture.
